UNITED STATES PATENT OFFICE

CHARLES D. FAGAN, OF SHARON, PENNSYLVANIA, ASSIGNOR TO SHARPSVILLE BOILER WORKS COMPANY, OF SHARPSVILLE, PENNSYLVANIA, A CORPORATION OF PENNSYLVANIA

DESIGN FOR A CASING FOR DISPENSING APPARATUS

Application filed December 10, 1929. Serial No. 33,736. Term of patent 14 years.

To all whom it may concern:

Be it known that I, CHARLES D. FAGAN, a citizen of the United States, residing at Sharon, in the county of Mercer, State of Pennsylvania, have invented a new, original, and ornamental Design for Casing for Dispensing Apparatus, of which the following is a specification, reference being had to the accompanying drawings, forming a part thereof.

Fig. 1 is a perspective view of a casing for

dispensing apparatus showing the front and side of my new design.

Fig. 2 is an elevational view showing the side of my new design.

Fig. 3 is a plan view showing the top of my new design.

I claim:

The ornamental design for a casing for dispensing apparatus as shown.

CHARLES D. FAGAN.
